US0D1028041S

(12) **United States Design Patent** (10) Patent No.: **US D1,028,041 S**
(45) Date of Patent: ** May 21, 2024

(54) **HORIZONTAL PEELER CENTRIFUGE FOR CHEMICAL APPLICATIONS**

(71) Applicant: **HEINKEL Holding GmbH**, Besigheim (DE)

(72) Inventors: **Tobias Hänele**, Besigheim (DE); **Tobias Hoffmann**, Talheim (DE); **Eugen Lehr**, Tamm (DE)

(73) Assignee: **HEINKEL Holding GmbH**, Besigheim (DE)

(**) Term: **15 Years**

(21) Appl. No.: **35/515,594**

(22) Filed: **May 12, 2022**

(80) **Hague Agreement Data**

Int. Filing Date: **May 12, 2022**

Int. Reg. No.: **DM/223157**

Int. Reg. Date: **May 12, 2022**

Int. Reg. Pub. Date: **Nov. 18, 2022**

(57) **CLAIM**

The ornamental design for a horizontal peeler centrifuge for chemical applications, as shown and described.

DESCRIPTION

1. Horizontal peeler centrifuge for chemical applications

1.1 is a front left top perspective view.

1.2 is a right side view.

1.3 is a left view.

1.4 is a front view.

1.5 is a top plan view.

1.6 is a bottom plan view.

1.7 is a rear view.

The broken lines indicate unclaimed portions of the invention and form no part of the claimed design.

1 Claim, 7 Drawing Sheets
